UNITED STATES PATENT OFFICE.

EDMUND CORBIN, OF CHICAGO, ILLINOIS.

CHAIR ATTACHMENT.

1,216,287.

Specification of Letters Patent. Patented Feb. 20, 1917.

Application filed March 17, 1916. Serial No. 84,842.

To all whom it may concern:

Be it known that I, EDMUND CORBIN, a citizen of the United States, residing at Chicago, in the county of Cook and State of Illinois, have invented new and useful Improvements in Chair Attachments, of which the following is a specification.

This invention relates to attachments for chairs in the nature of an auxiliary seat positioned above the regular seat of the chair, to convert the chair into a high chair for the use of children or persons of very short stature. The attachment is primarily designed for use in connection with auditorium chairs which are too low to afford an unobstructed view to children or short persons. The attachment is also applicable to kitchen, dining room or other domestic chairs for converting the same into an infant's or child's high chair.

The invention has for its object to provide a simple, cheap and efficient attachment of the kind stated, and one which can be readily applied to the chair and removed therefrom.

The invention also has for its object to provide an attachment which is foldable, so that when it is applied to an auditorium chair, it need not be removed therefrom if the regular seat of the chair is to be used.

With the objects stated in view, the invention consists in a novel combination and arrangement of parts to be hereinafter described and claimed, and in order that the same may be better understood, reference is had to the accompanying drawings, forming a part of this specification.

In the drawings—

Figure 1 is a perspective view showing the attachment applied to an auditorium chair;

Fig. 2 is a vertical section showing the attachment folded;

Fig. 3 is a sectional detail showing a latch;

Fig. 4 is a cross-section on the line 4—4 of Fig. 1;

Fig. 5 is a perspective view showing the attachment applied to a domestic chair; and

Fig. 6 is a side elevation showing the attachment folded.

Referring specifically to the drawings, 10 denotes an ordinary auditorium chair having a back 11 and a foldable seat 12. The auxiliary seat attachment comprises a supporting frame carrying a seat bottom 13 and a foot rest 14, and provided with means for

attachment to the chair back 11. The supporting frame consists of two laterally spaced standards 15 having each at the top a hook 16 engageable over the top edge of 60 the chair back 11. The hooks 16 are connected by a cross bar 17 extending across the chair back 11 behind the same, and serving to stiffen the supporting frame and to prevent rattling. The cross bar 17 is flexible to fit the curve of the chair back 11.

The seat bottom 13 is pivotally connected, as shown at 18, to lugs 19 on the standards 15, and the foot rest 14 is pivoted, as shown at 20, to lugs 21 on said standards at the 70 bottom thereof. The length of the standards 15 is such that the foot rest 14 seats on the seat bottom 12, and the latter therefore assists to support the attachment, so that it is firmly held in place when applied to the 75 chair.

The seat bottom 13 and the foot rest 14 are connected at their side edges by links 22, the latter being pivoted to said parts in any suitable manner as shown at 23. The 80 links 22 extend above the seat bottom 13, and their upper ends are connected by links 24 to the standards 15, the latter having lugs 25 to which the rear ends of the links are pivoted as shown at 26, their front ends being pivotally connected to the links 22 as shown at 27. The links 22 rise to such a height above the seat bottom 13 that the links 24 serve as arm rests.

The attachment hereinbefore described is 90 foldable when not in use, and it may remain on the chair 10 in folded position, as it does not take up enough space to interfere with a person occupying the seat 12, nor does it interfere with the folding of said seat, as it 95 is back of the hinge of the latter. As shown in Fig. 2, the seat bottom 13 and the foot rest 14 fold together against the seat back 11, the seat bottom being next to the latter, and the foot rest being in front of the seat 100 bottom, the folded parts now serving as the back rest of the chair 10. In order that this back rest formed by the folded parts may be smooth, the under side of the seat bottom 13 is reduced in thickness, as indicated 105 at 28, forming a recess in which the folded foot rest 14 seats.

In order to hold the attachment in folded position, the seat bottom 13 has a suitable spring latch hook 29 which catches in an 110 aperture 30 in the foot rest 14.

The shoulder formed by the reduced por-

tion 28 of the seat bottom 13 has a recess 31, which latter, when the parts are folded, permits ready access to the upper edge of the foot rest 14 for grasping the same to swing it down into position for use.

The standards 15 are, preferably, channel bars, as shown in Fig. 4, the channels, however, being discontinued at the hooks 16.

The auxiliary seat attachment hereinbefore described can be readily applied to any ordinary auditorium chair, and by its use the chair may be converted to a high chair suitable for a child or a person of such short stature that the seat 12 would be too low to afford an unobstructed view. The attachment is not a permanent fixture, but may be readily removed if desired, although, as already stated, it may remain, as it can be folded so as not to interfere with a person occupying the seat 12.

The attachment is strong and durable, and the arm and foot rest insure safety and comfort of the child or other person occupying the auxiliary seat 13. The parts are securely connected, and designed to safely carry the weight of the occupant. The cross bar 17 may be used for holding advertising matter. The foot rest 14 prevents the feet of the occupant of the seat 13 from coming in contact with the seat 12, and the latter is therefore prevented from being scratched or marred.

Figs. 5 and 6 illustrate the attachment applied to an ordinary dining room, kitchen or other domestic chair 32, for converting the same into a high chair, the standards 15 being hooked over the top of the chair back

33 as before. The foot rest 14, however, does not seat on the chair bottom 34, but is spaced slightly therefrom, in view of which a foldable brace is provided, the same comprising two links 35 which are pivotally connected as indicated at 36. One of the links is pivotally connected to the lug 19, as shown at 37, and the other link is connected to the foot rest as shown at 38, this being also the pivot of the links 22. These brace links are located on both sides of the attachment.

I claim:

1. An auxiliary seat attachment for chairs, comprising a support having means for attachment to the chair, and a pivoted seat and a pivoted foot rest carried by the support and foldable flush with each other against the back of the chair.

2. An auxiliary seat attachment for chairs, comprising a support having means for attachment to the chair, and a pivoted seat and a pivoted foot rest carried by the support and foldable on each other and against the back of the chair, the seat having a bottom recess to accommodate the folded foot rest.

3. An auxiliary seat attachment for chairs having a foldable seat, comprising a pivoted seat and a pivoted foot rest, foldable flush with each other against the back of the chair, and means for supporting the attachment on the chair back of the pivot of the seat of the latter.

In testimony whereof I affix my signature.

EDMUND CORBIN.
